J. J. L. Wright

UNITED STATES PATENT OFFICE

STONEWALL J. McSPADDEN, OF ALPINE, TEXAS

BUILDER'S STRAIGHT-WIRE ANCHOR

Application filed May 31, 1930. Serial No. 458,714.

The object of this, my present invention, is the provision of anchoring means for straight wires such as are employed for making concrete forms or the like, and the object of the invention is the provision of a simple means for this purpose which will grippingly engage with ends of wires, each cut at a similar length, and effectively hold such wires on and between a form or the like.

10 A further object is the provision of a clamping means for this purpose that comprises a flared or substantially cone-shaped member divided in halves, the confronting faces of each half or section having intermeshing teeth, the said half or section designed to receive the ends of form wires therebetween and the said sections being removably held together and the teeth thereof in biting engagement with the ends of the wire 15 through the medium of a ring which wedgingly engages the clamp.

To the attainment of the foregoing the invention consists in the improvement herein-after described and definitely claimed.

20 In the drawings:

Figure 1 is a perspective view illustrating the application of my improvement in connection with a concrete form.

Figure 2 is a transverse sectional view 30 therethrough.

Figure 3 is an enlarged side elevation of the improvement.

Figure 4 is a face view looking toward the toothed face of one of the sections of the 35 clamp.

Figure 5 is a sectional view approximately on the line 5—5 of Figure 3.

While I have illustrated, in Figures 1 and 2 of the drawings, my improvement employed 40 for holding the ends of wires that sustain the vertical posts in a concrete form against the longitudinal boards thereof, it is to be understood that the improvement is not to be restricted to this particular arrangement as 45 the same may be successfully employed in other connections where the ends of wires either permanently fixed or removable are to be clamped.

When employed in connection with a form 50 it will be further understood as the concrete

sets the clamps may be removed from the lower wires and employed to engage with the upper wires of the form. It will be also noted that the wires may be all cut the same length.

The side boards of a concrete form are indicated by the numeral 1, the vertical posts by the numeral 2 and the spacer plates by the numeral 3. The spacer plates are, of course, removable and also the uprights 2 are not nailed or otherwise connected to the boards 1. At determined spaces throughout the length of the posts or uprights 2 and the boards 1 I bore alining holes and through these holes there are passed the usual holding wires 4. These wires, as stated, are all of the same length and have their ends projecting each a suitable distance beyond the posts or uprights 2 and it is these ends that the clamp constituting my improvement engages.

As disclosed by the drawings the clamp 70 comprises a flared or substantially cone-shaped member which is round in plan. The clamp comprises two halves or sections 5, respectively, and the flat confronting faces of these sides are provided with transversely arranged intermeshing teeth 6 and between the sections 5 the ends of the wires 4 are received. The widened ends of the clamps are forced against the posts or uprights 2 and the sections 5 are slightly canted on each other 75 as disclosed by Figure 5 of the drawings. Thereafter I arrange over the outer or nose end of the clamp a metal ring 7 and this ring is forced longitudinally over the clamp to bring the sections 5 thereof toward each other 80 to cause the interengaging teeth to bite into the wire but such frictional engagement between the teeth and wire is not sufficient to sever the wire as the confronting faces of the clamps are at all times retained angularly 85 with respect to each other, as disclosed by Figure 5 of the drawings.

It is thought the simplicity and advantages of the construction will be apparent to those skilled in the art to which such invention relates so that further detailed description will not be required.

Having described the invention, I claim:

A means for clamping the projecting ends of wires to a form or the like, comprising a

substantially frusto conical member divided
into halves and each section having its flat
confronting face provided with transverse
teeth to receive the wire therebetween and a
5 wedge ring arranged over the clamp for hold-
ing the confronting faces of the clamp in bit-
ing engagement with the wire but in angular
relation to each other.

In testimony whereof I affix my signature.
10 STONEWALL J. McSPADDEN.
